UNITED STATES PATENT OFFICE

WILLIAM E. WINE, OF TOLEDO, OHIO

HOPPER CAR CONSTRUCTION

Application filed February 12, 1929. Serial No. 339,348.

My invention relates to railway hopper car construction and more particularly to doors for such cars. The principal object of the invention is to provide a strong and simple integrally formed metal door. Another object of the invention is to provide means for connecting the doors of hoppers which are disposed on opposite sides of the car center sill.

10 A principal feature of the invention consists in integrally forming a hopper car door with a stiffening member adjacent its lower edge.

Another feature of the invention resides 15 in integrally forming a hopper car door with an angularly shaped stiffening member, one end of said member projecting beyond the side of the door to form means for cooperating with a hook to support the door in closed position.

20 A further feature of the invention consists in integrally forming a hopper car door with a stiffening member adjacent its lower edge and with reinforcing flanges respectively 25 projecting from opposite sides of said stiffening member.

A still further feature of the invention resides in providing the adjacent doors of 30 a hopper car which are disposed on opposite sides of the car center sill with outwardly projecting stiffening members, means being rigidly secured to each of said stiffening members for connecting the doors to cause them to swing as one.

35 Other features of the invention residing in advantageous forms and combinations and relations of parts will hereinafter appear and be pointed out in the claims.

In the drawings illustrating a preferred 40 embodiment of the invention.

Figure 1 is a transverse sectional view of the lower portion of one-half of a hopper car, the door and its frame being in elevation and the floor sheet of the car being omitted.

Figure 2 is a fragmentary side elevational view of the construction illustrated in Figure 1.

Figure 3 is a front elevational view of the 50 cast metal door and a portion of the member for connecting doors on opposite sides of the car center sill.

Figure 4 is a side elevational view thereof.

Figure 5 is a sectional view taken on line 55 5—5, Figure 3.

Figure 6 is a side elevational view of the lower portion of the inner edge of the door, the connecting member being in section.

Figure 7 is an enlarged detail front elevational view of one of the upper corners of 60 the door frame.

Figure 8 is a side elevational view of the construction illustrated in Figure 7.

Figure 9 is a sectional view taken on line 65 9—9, Figure 7.

Figure 10 is a diagrammatic view taken transversely of the car illustrating the arrangement of the hoppers on opposite sides of the car center sill and the manner in which 70 the hopper doors are connected.

While substantially only one-half of the lower portion of the hopper car has been illustrated it is to be understood that the construction is duplicated on the other side of the car, as will be appreciated from Figure 10, and that the upper portion of the car 75 may be of any desired construction.

In the drawings 1 indicates the car center sill and 2 the car side sill, the latter preferably having an upwardly projecting flange 3 to which side sheets 4 of the car may be secured by rivets 5. The hopper is formed by an inclined bottom or slope sheet 6 and inner and outer side sheets 7 and 8 respectively. The side sheets of the hopper converge downwardly and each is provided along its lower edge with an inwardly projecting flange 9 which lies beneath and is secured by any suitable means to the slope sheet 6.

The inner side sheet 7 terminates at its 90 upper edge in a substantially vertical flange 10 which is secured to the center sill of the car by rivets 11. The outer side sheet 8 is bent outwardly as at 12 to pass above the side sill 2 in close proximity thereto and it 95 terminates in an upwardly projecting flange 13 rigidly secured to the side sheets 4 of the car by rivets 14.

The car is provided with an inclined floor plate 15, the lower edge of which together with the marginal edges of the side and slope sheets of the hopper define an opening with 100 which the door frame, to be hereinafter described, is associated. Above the opening the side sheets of the hopper have inwardly extending flanges 16 which are disposed beneath and secured to the floor plate 15 by rivets 17.

The upper outer corner of the opening may advantageously be reinforced 105 by an angular shaped member 18 having 110

flanges 19 and 20 respectively secured by rivets 21 and 22 to the inner face of the side sheet 8 and the upper face of the floor sheet 15. If desired the floor sheet may be rigidified by an angle iron 23 secured thereto by the rivets 17 and 22.

Rigidly secured to the floor sheet 15 of the car and the side sheets 7 and 8 and slope sheet 6 of the hopper, by rivets 24, is a door frame 25 which is preferably cast as an integral unit. The frame is of substantially trapezoidal form and is preferably symmetrical about its vertical axis so that it may be interchangeably mounted upon either side of the car center sill. It will therefore be appreciated that since the frame is symmetrical some portions thereof will be without function when mounted on one side of the car but they will perform their intended functions when the frame is mounted on the opposite side. At its opposite sides and bottom edge the frame is provided with inwardly projecting flanges 26 and 27, respectively, for receiving the attaching rivets 24. At its upper edge the frame is provided with an outwardly inclined portion 28 terminating in a flange 29, the portion 28 being disposed in a plane substantially parallel with that of the floor sheet 15 of the car and affording means for receiving the rivets for attaching the frame thereto. The opposite ends of the inclined portion 28 are depressed as at 30 to receive adjacent portions of the flanges 16 of the upper side sheets. Adjacent their upper ends the sides of the frame are respectively provided with outwardly projecting portions 31 forming pads or the like having substantially vertical outer surfaces, the projections being apertured to receive rivets 32 for connecting the frame directly to the center sill. From the foregoing it will be perceived that the frame is so designed that it may be connected to the car structure and hopper in a very rigid manner.

The frame is formed with a lading discharge opening which is preferably of rectangular shape, thereby providing on opposite sides of the opening substantially triangular downwardly tapering portions 33 intervening between the opening and the respective hopper side sheets. In order to reinforce the lower part of the door frame it may advantageously be provided with a flange 34 which passes under the door opening and extends upwardly for a distance at opposite sides of the frame as indicated at 35. As will be readily understood these flange portions 35 serve to reinforce the lower corners of the frame. At its upper corner the frame may be rigidified by substantially vertical flanges 36 which extend downwardly from the ends of the top flange 29 and merge into triangular portions 33. Outwardly of the vertical flanges 36 the top portion of the frame inclines outwardly and downwardly

as at 37 intersecting the sides of the frame at substantially right angles and at these points of intersection the frame may be reinforced by angular flanges 38.

Intermediate the top and bottom of the frame the side flanges 26 are fashioned to accommodate a door locking mechanism which may be of any convenient design. The mechanism illustrated in the present case involves a cover plate or bracket 39 which is secured in spaced relation to the adjacent side flange by a plurality of rivets 40. Interposed between the flange and cover plate is a pivoted hook 41 and a pivoted locking cam 42 which may be conveniently mounted on two of the attaching rivets 40. The hook may advantageously be provided with a plurality of ledges 43 for cooperating with a portion of the hopper door, to be hereinafter described, to support it in either partially closed or fully closed position and the cover plate 39 may be formed with an outwardly projecting apertured lug 44 for cooperating with a removable lever for forcing the door from partially closed to fully closed position.

The door 45 for closing the lading discharge opening of the hopper is cast as a unitary structure and is provided with inwardly projecting flanges 46 for cooperating with outwardly projecting flanges 47 bordering the opening of the frame to prevent the escape of fine lading from the car. The door is preferably fashioned with upwardly projecting lugs or studs 55 adapted to be respectively interposed between pairs of lugs 56 formed integrally with the door frame, all of the lugs being apertured to receive removable pins 57 for hingedly mounting the door. Adjacent its lower edge the door is integrally formed with an angularly shaped stiffening member 48 having an outwardly projecting web or flange portion 49 arranged substantially normal to the door and a downwardly projecting flange 50 spaced outwardly from the door and preferably disposed in a plane parallel therewith. The web 49 may conveniently decrease in width from a point substantially midway between the side edges of the door to adjacent the outer side edge thereof while the flange 50 may decrease in depth from points inwardly of the side edges of the door to points respectively adjacent said edges.

One end of the stiffening member 48 projects laterally beyond a side edge of the door to form an arm 51 having a plurality of upwardly projecting spaced flanges 52 and 53, respectively. The flange 52 is spaced outwardly from the door and extends from a point inwardly of the side edge thereof and of the adjacent end of flange 50 to a point adjacent the end of the arm while the flange 53 is disposed inwardly of the outer face of the door and is adapted to cooperate with the ledges of the hook 41 to sustain the door.

in either partially closed or fully closed position. At its inner end the flange 53 is formed integral with the adjacent side flange 46 of the door and at its outer end it is connected to the flange 52 by an angular end wall 54. The upper edge of a portion of the end wall may be advantageously ribbed to afford a tread so that an operator may rest his foot thereon to apply force to swing the door to a closed position.

The doors of adjacent hoppers on opposite sides of the car center sill are connected by a rigid member 58 to cause the doors to swing as one. As most clearly shown in the diagrammatic view of Figure 10 the two doors and their connecting member 58 may be regarded, for all practical purposes, as a door device of which the two doors are but sections. The connecting member is interposed between the outer face of the door and the inner face of the flange 50 of the stiffening member and it may advantageously be a commercial bulb angle so arranged that one of its flanges 59 is disposed substantially parallel to the outer face of the door and the other of its flanges 60 parallel with the web portion 49 of the stiffening member, the bulb of the angle being disposed adjacent the down-turned flange 50 of the latter. The member 58 is preferably connected to each of the door sections by rivets 61 passing through the outwardly projecting flange 49 of the stiffening member and the flange 60 of the connecting member. To relieve the attaching rivets 61 from excessive shearing stresses the outer face of the door and the inner face of the down-turned flange 50 are respectively provided with protuberances 62 and 63 constituting abutments for the connecting member, the protuberance 63 coacting with the bulb of the latter and being disposed inwardly of the protuberance 62 which coacts with the flange 59 thereof. As forces of relatively great magnitude are transmitted from the doors to the connecting member, the latter overlaps each of the doors for a considerable extent and the stiffening members 48 are of greatest width adjacent the connecting member. Moreover, the stiffening member of each of the doors is preferably reinforced adjacent the abutment 63 with an upstanding rib 64.

Projecting from opposite sides of the stiffening member 48 are a plurality of rigidifying and strengthening ribs or flanges 65 and 66, respectively, the flanges 65 extending between the stiffening member and the upper edge of the door and the flanges 66 extending between the stiffening member and the lower edge of the door. While the door may be integrally formed with any number of the flanges 65, three have been found sufficient and it is preferred to arrange two of the flanges so that they will merge into the hinge lugs 55 to reinforce the latter. The flanges

66 are preferably disposed in alignment with the flanges 65 so as to constitute prolongations thereof but it is to be observed that the portion of the door adjacent the inner edge thereof is not formed with a flange as to locate one there in alignment with the innermost one of the flanges 65 would interfere with the attachment of the connecting member 58 to the door. It will be perceived that by arranging the flanges 65 and 66 in alignment with each other, in addition to strengthening the door, they rigidify the stiffening member 48 against torsional and other forces which may be imparted to it. The flanges 65 and 66 may respectively decrease in depth from adjacent the stiffening member toward their ends and while they may terminate short of the edges of the door it is deemed preferable to continue them to adjacent the edges.

From the foregoing it will be appreciated that both the door and its frame are constructed in a manner so that they will withstand rough usage and that the latter effectively rigidifies the discharge end of the hopper.

I claim:

1. A hopper car door having a stiffening member formed integrally therewith adjacent its lower edge, said stiffening member being of angular shape and extending substantially continuously from adjacent one side edge of the door to adjacent its opposite edge.

2. A hopper car door having an angular reinforcing member formed integrally therewith, said member projecting beyond one of the side edges of the door to form means for cooperating with a movable door supporting device mounted upon the car.

3. A hopper car door having an angularly shaped reinforcing member formed integrally therewith, said member extending continuously from adjacent one side edge of the door to a point outwardly of the opposite side edge thereof, said projecting portion of the member affording means for cooperating with mechanism carried by the hopper for supporting the door in closed position.

4. An integrally formed hopper car door having an angularly shaped reinforcing member and a plurality of flanges respectively projecting from opposite sides of the stiffening member.

5. An integrally formed hopper car door including lugs for pivotally connecting the door to the car, an outwardly projecting angularly-shaped stiffening member, and flanges respectively connecting said lugs and said member.

6. An integrally formed hopper car door including an outwardly projecting angularly-shaped stiffening member and a plurality of flanges respectively extending from op-

- posite sides of said member to the upper and lower edges of the door.
7. An integrally formed hopper car door including an angularly shaped stiffening member having one end projecting beyond a side edge of the door for cooperating with means carried by the car body to support the door in closed position, and a plurality of flanges substantially normal to said member and respectively extending from opposite sides thereof. 70
8. An integrally formed hopper car door having a stiffening member adjacent the lower edge thereof, said member being of varying width and being widest adjacent the inner edge of the door. 75
9. An integrally formed hopper car door having a stiffening member adjacent the lower edge of the door, said member having a portion projecting outwardly from the door and terminating in a downwardly directed flange, said flange decreasing in depth adjacent its opposite ends. 80
10. An integrally formed car door adapted to be hingedly associated with a hopper, said door including inwardly projecting marginal flanges, an outwardly projecting stiffening member disposed adjacent to and extending substantially parallel with the free edge of the door, and a plurality of flanges respectively projecting from opposite sides of said member, said flanges being of greater depth adjacent the said member than adjacent their extremities. 85
11. An integrally formed hopper car door having inwardly projecting marginal flanges and a laterally projecting arm provided with an upwardly projecting flange disposed inwardly of the outer face of the door, said flange affording means for cooperating with a hook pivotally mounted upon the car body to support the door in closed position. 90
12. A hopper car door integrally formed with a stiffening member having a portion projecting beyond a side edge of the door, said projecting portion being provided with a plurality of flanges one of which affords means for cooperating with mechanism carried by the hopper to support the door in closed position. 95
13. A door device for railway hopper cars involving a plurality of door sections for respectively closing lading discharge openings, disposed on opposite sides of the car center sill, each of said doors being integrally formed with an outwardly projecting stiffening member, and means rigidly connecting said door sections, said means being respectively secured to the door stiffening members adjacent their inner ends. 100
14. A door device for railway hopper cars involving a plurality of door sections for respectively closing lading discharge openings disposed on opposite sides of the car center sill, each of said doors being integrally formed with a stiffening member having a portion projecting outwardly from the door and terminating in a downwardly projecting flange, and rigid means respectively connecting said doors, said means being disposed between the outer face of each door and the downwardly projecting flange of its stiffening member. 105
15. A door device for railway hopper cars involving a plurality of door sections for respectively closing lading discharge openings disposed on opposite sides of the car center sill, each of said door sections being integrally provided with a stiffening member having a downwardly projecting flange disposed in spaced relation to the outer face of the door, and rigid means respectively connecting said door sections, the outer face of said door and the inner face of said flange being provided with abutments for cooperating with said connecting means. 110
16. A door device for railway hopper cars involving a plurality of door sections for respectively closing lading discharge openings disposed on opposite sides of the car center sill, each of said doors being integrally formed with a stiffening member having a web portion and a downwardly projecting flange disposed in spaced relation to the outer face of the door, and rigid means for connecting said doors, said means being respectively secured to the web portion of said stiffening members and being disposed between the outer face of the doors and the said downwardly projecting flange of the stiffening members, the outer face of each of said doors and the inner face of each of said flanges being fashioned with abutments for cooperating with said means and each of said stiffening members being fashioned with an upstanding rib adjacent the abutment on the flange thereof. 115
17. A door device for railway hopper cars involving a plurality of door sections for respectively closing lading discharge openings disposed on opposite sides of the car center sill, each of said doors being integrally provided with an outwardly projecting stiffening member, and means rigidly secured to each of said stiffening members for connecting the doors, said stiffening members decreasing in width from adjacent the inner end of said means toward their respective outer ends. 120
18. A hopper car door integrally formed with a stiffening member having a downwardly projecting flange, a portion of said member extending beyond a side edge of the door and provided with spaced upwardly projecting flanges, one of said last-named flanges constituting a prolongation of said downwardly projecting flange and the other affording means for cooperating with mechanism carried by the hopper to support the door in closed position. 125
- In testimony whereof I affix my signature.
WILLIAM E. WINE. 130
